[21] Appl. No.: 962,150

[57] CLAIM

[22] Filed: Nov. 20, 1978

The ornamental design for an electronic calculating
machine, as shown and described.

[30] Foreign Application Priority Data

Nov. 24, 1978 [JP] Japan 53/21477

DESCRIPTION

[51] Int. Cl. ..... D18—01

FIG. 1 is a perspective view of an electronic calculating
machine showing my new design;

[52] U.S. Cl. D18/7

FIG. 2 is a top plan view thereof;

[58] Field of Search D18/2, 6-8,

D18/11, 12; D14/45; 364/706-710; 200/5 A

FIG. 3 is a front elevational view thereof;

[56] References Cited

FIG. 4 is a rear elevational view thereof;

U.S. PATENT DOCUMENTS

FIG. 5 is a right side elevational view thereof;

D. 218,785 9/1970 Gore D18/7

FIG. 6 is a left side elevational view thereof; and

D. 247,391 2/1978 Hazama et al. D18/7

FIG. 7 is a bottom plan view.
